UNITED STATES PATENT OFFICE

CLARENCE L. TAYLOR, OF YOUNGSTOWN, OHIO

CONTROLLING MEANS FOR ELECTRIC CONDUCTORS

Application filed June 22, 1929, Serial No. 372,876. Renewed December 5, 1931.

My invention relates to means for controlling electric conductors connected to traveling devices. I have illustrated this invention as applied to a trolley on a traveling crane, but it is to be understood that the invention may be applied to other structures than cranes.

There has heretofore been considerable difficulty in properly taking care of the various electric conductors which are connected to electrically-controlled trolleys having travel on the beams or bridges of traveling cranes. If the conductors are suspended from the trolleys they are more or less dangerous to life and property and are liable to become entangled with various things and become damaged or broken. Shoes carried by the trolley and making electric contact with a third rail are not entirely satisfactory, particularly where several shoes are required to carry separate currents for several electrical devices mounted on the trolley. Other means have been devised for the same purpose, but they are not wholly satisfactory.

It is the object of this invention to do away with suspended conductors, shoes, and other devices in the present practice for connecting electrical elements on a traveling device, as a crane trolley, to suitable sources of current, and to provide in their stead a means which permits the ends of the conductors attached to the traveling device to travel therewith and at the same time causes the portions of the conductors between the traveling device and certain fixed points to move within confined and protected paths. Another object is to provide conductors of fixed lengths between the trolley and the said points without requiring any substantial slack in the conductors. It is one object to prevent slack in the said conductors by taking it up as it tends to be created. This I prefer to do by means of a carriage operated by the traveling device through draft exerted by the conductors or by a special draft cable accompanying the conductors, as hereinafter described.

Referring to the accompanying drawing, Fig. 1 is an end elevation of a traveling

crane equipped with the preferred form of my invention, the trolley being centrally between its limits of travel; Fig. 2, a fragmentary enlarged sectional view showing one of the carriage rollers in its relation to adjacent elements. Fig. 3, a diagrammatic view showing the position of the trolley, the carriage and the conductors when the trolley is at one limit of its travel; and Fig. 4, a view similar to Fig. 3, but with the trolley at the other limit of its travel.

On the drawing, 1 designates the runways supporting the rails 2 on which the wheels 3 of the bridge 4 of a traveling crane move. 5 is a trolley having travel on rails (one only marked 6 being shown) on the bridge 4 transversely of the runways, and 6 is the crane operator's cab. The apparatus so far described is old.

One side of the bridge 4 is provided with the long shelf-like bracket 7 having thereon the rails 8 parallel with the bridge and the travel of the trolley. A number of parallel rollers 9 have travel on the rails 8. The rollers have annular flanges 10 bearing against the opposing faces of the rails to guide the rollers in their travel on the rails. The rollers have axles 11 whose ends project through and beyond the side bars or frame members 12 which lie at the ends of the rollers. Cotter-pins 13 prevent the separation of the axles and the frame members. The rollers 9 and the side bars or frame members constitute a carriage indicated as a whole by the numeral 14.

The trolley 5 has the arm 15 extending out laterally therefrom and downwardly close to a plane including the upper surface of the rollers.

From the cab 22 to the trolley 5 there will be sufficient conductors or cables carrying conductors to supply current to the electric motor or motors on the trolley and to such other electrical devices as may be carried thereon. To simplify the description it will be assumed for the present that only two conductors 16 and 17 are connected to the trolley and the cab, though there may be more than one, as shown in Fig. 2. The conductors are clamped to the bridge below the carriage 14 by any

suitable means, as the plate 18. They are clamped mid-way between the ends of the bridge. The conductors pass right and left respectively on the rollers 19 which are mounted between the rails 8 and below the carriage 14. The conductors thence pass respectively up over the end rollers 9 of the carriage and thence toward each other on the rollers 9 to the arm 15 up which they pass to the trolley 5 to which or the arm 15 they are secured. Other conductors as 20 and 21 may accompany the conductors 16 and 17 as in Fig. 2 where three conductors or cables containing conductors are shown. The conductors should all be insulated in the usual or any preferred manner.

Assuming current is supplied to the trolley to move it to the left from its central position shown in Fig. 1, the trolley will pull the upper leg of the conductor 16 to the left which will cause this conductor by its action on the right hand roller 9 to move the carriage 14 to the left, the carriage obviously moving half the distance the trolley travels. As the trolley travels to the left, the lower leg of the conductor 16 becomes progressively the upper leg, while the upper leg of the conductor 17 becomes progressively the lower leg. Preferably the conductors are reasonably taut so as to prevent backlash when the trolley moves in either direction. In case there are more than one conductor or there are cables containing more than one conductor, they will all be arranged like the conductors 16 and 17 and may all become draft lines for operating the carriage. If preferred, one of the conductors or cables could be a steel draft cable to relieve the current-carrying conductors from strain. Fig. 4 shows the positions of the trolley, the carriage and the conductors 16 and 17 when the trolley has moved substantially to its right hand limit.

I have not shown the elements to which the conductors are connected on the trolley, nor have I shown any controller for distributing current to the said elements, nor have I shown the main current supply lines for the various elements since they are all well known and can be applied by anyone skilled in the art to which this invention appertains.

I claim:

1. In combination, a traveling means, a carriage movable parallel with the traveling means, two draft lines, each having one end attached to the traveling means and its other end fixedly secured to the opposite side of the carriage from the traveling means, the intermediate portions of the draft lines being formed into U-shaped loops loosely engaging the respective ends of the carriage, whereby the movement of the traveling means causes one draft line or the other to move the carriage.

2. In combination, an electrically operated

traveling means, a carriage movable parallel with the traveling means, two draft lines constituting conductors of electricity for controlling the traveling means, each having one end attached to the traveling means and its other end fixedly secured to the opposite side of the carriage from the traveling means, the intermediate portions of the draft lines being formed into U-shaped loops loosely engaging the respective ends of the carriage, whereby the movement of the traveling means causes one draft line or the other to move the carriage. 70

3. In combination, a traveling means, a carriage movable parallel with the traveling means, a closed loop loosely embracing the carriage and extending in the direction of its travel, a fixed support for the loop at one side of the carriage, the loop at the opposite side of the carriage being secured to the traveling means. 80

4. In combination, an electrically controlled traveling means, a carriage movable parallel with the traveling means, a closed loop loosely embracing the carriage and extending in the direction of its travel, a fixed support for the loop at one side of the carriage, the loop at the opposite side of the carriage being secured to the traveling means, and the loop comprising separate insulated electric conductors from the said support to the traveling means. 90

5. In combination, a traveling crane containing a bridge and an electrically controlled trolley having travel thereon, a carriage having travel on the bridge below the trolley, a pair of electric conductors attached to the bridge below the carriage and respectively loosely passing right and left beneath the carriage and over the ends thereof and above the carriage and being attached to the trolley. 100

In testimony whereof, I hereunto affix my signature.
